Primary Examiner — Susan Moon Lee(74) *Attorney, Agent, or Firm* — Duane Morris LLP**CLAIM**

The ornamental design for a portable terminal, as shown and described in the Figures.

DESCRIPTION

FIG. 1 is a perspective front view of a portable terminal according to the present invention.

FIG. 2 is a perspective rear view of the portable terminal of FIG. 1.

FIG. 3 is a front view of the portable terminal of FIG. 1.

FIG. 4 is a rear view of the portable terminal of FIG. 1.

FIG. 5 is a right side view of the portable terminal of FIG. 1.

FIG. 6 is a left side view of the portable terminal of FIG. 1.

FIG. 7 is a top view of the portable terminal of FIG. 1; and,

FIG. 8 is a bottom view of the portable terminal of FIG. 1.

The portions shown in broken line are not claimed.
